Primary Examiner—Ted Shooman*Assistant Examiner*—Richelle Shelton*Attorney, Agent, or Firm*—Foley & Lardner[57]*CLAIM

I claim the ornamental design for the beverage container case, as shown and described.

DESCRIPTION

FIG. 1 is a perspective view of a beverage container case showing my new design;

FIG. 2 is a side elevation view thereof, the opposite side elevation view being identical;

FIG. 3 is a top plan view thereof;

FIG. 4 is an end elevation view thereof, the opposite end elevation view being identical;

FIG. 5 is a bottom plan view thereof; and,

FIG. 6 is a side elevation view thereof, shown nested.

The broken line showing of portions of the beverage container case in FIGS. 1-6 is for illustrative purposes only and forms no part of the claimed design.
